UNITED STATES PATENT OFFICE.

PETER L. LARSON, OF DES MOINES, IOWA.

COUNTERBALANCING STAIR OR LADDER FOR FIRE-ESCAPES.

SPECIFICATION forming part of Letters Patent No. 752,082, dated February 16, 1904.

Application filed March 5, 1902. Serial No. 96,759. (No model.)

To all whom it may concern:

Be it known that I, PETER L. LARSON, a citizen of the United States of America, and a resident of Des Moines, Polk county, Iowa, 5 have invented a new and useful Counterbalancing Stair or Ladder for Fire-Escapes, of which the following is a specification.

The object of this invention is to provide improved means of construction for a counterbalanced stair or ladder for fire-escapes in which the minimum of force will be required to swing the said ladder or stair angularly.

My invention consists of the construction, arrangement, and combination of elements hereinafter set forth, pointed out in my claims, and illustrated by the accompanying drawings, in which—

Figure 1 is a side elevation illustrating my improved device, the dotted lines showing the position assumed by the device under an angular adjustment of the stair or ladder. Fig. 2 is a top view of one form of my improved stair or ladder, illustrating the means employed to sustain the alinement of the ladder-bars.

In the construction of the device, as shown, the numeral 10 designates a pivot-rod arranged for mounting with one end in the wall of a building and the opposite end braced by brackets 11, 12 to said wall. A ladder or stair is provided composed of side bars 13, 14, connected by steps or rungs 15 in any ordinary and desirable manner. The side bars 13, 14 of the stair or ladder are pivotally connected at one end to the pivot-rod 10, and an extension-arm 16 is fixed to the pivoted end of the side bar 14 and extends therefrom in an opposite direction from the pivot-rod. The extension-arm 16 preferably is in longitudinal alinement with the side bar 14. The weight of the extension-arm 16 approximates closely to the weight of the ladder or stair, and a truss-rod 17 is fixed at its ends to the opposite extremities, respectively, of the side bar 14 and the extension-arm. The application or connection of the extension-arm 16 to one only of the side bars of the ladder or stair has the effect of permitting a twist or wind of said stair in respect of a drooping of the

free end of the side bar 13. To overcome such drooping of the free end of the side bar 13, I mount a steel rod 18 with one angular end fixed against rotation in a bracket 19 on one round or step of the ladder adjacent the pivot-rod 10, and the other angular end of said rod is passed through an angular seat in a bracket 20, fixed to one round or step of the ladder adjacent the free end thereof. The steel rod 18 is twisted relative to its longitudinal center in the direction in which the stair or ladder tends to twist or wind prior to the securing of the bracket 20 to the step or rung and then the torsional resilience or twist of the rod 18 tends to neutralize, overcome, and compensate for the normal twist of the ladder or stair and preserve the alinement and parallel positioning of the side bar 13 relative to the side bar 14. A hanger 21 is mounted on and embraces the truss-rod 17, and a disk weight 22 is mounted on and supported by said hanger and depends between the truss-rod and the inner end of the extension-arm 16. The hanger 21 is adjustable longitudinally of the truss-rod 17 within the limits of the space between the struts 23, 24, supporting said truss-rod, and said hanger may be locked in any given position by means of keys 25, wedges, or other desired fastenings, whereby it is connected to the truss-rod.

When the stair is in a horizontal position, as shown by solid lines in Fig. 1, the hanger is attached to the truss-rod 17 at a point in the rear of and above the pivot-rod 10, and the weight of the disk 22 is such that it effectually holds the ladder or stair in such horizontal position. The length of the struts 23, 24 is such that when the free end of the ladder or stair is drawn downward, as illustrated by dotted lines in Fig. 1, the weight-disk may swing forward across the axis of the pivot-rod 10 and overcome the equilibrium of the stair in the end of holding said stair in such inclined position. By reason of the change of positions of the weight-disk 22 said weight-disk will hold the ladder or stair in either a horizontal or radically-inclined position.

Normally the ladder or stair would be horizontal at an altitude out of the reach of a per-

son on the ground. A person could approach the upper end of the ladder or stair from a window or other opening in the wall of a building and tilt said ladder or stair by an application of manual force to the truss-rod 17, which also serves as a hand-rail, or the ladder may be tilted by the person stepping on the rungs thereof. The ladder may also be tilted downward by a fireman applying a fireman's hook to the free end thereof. The weight-disk ordinarily is so adjusted relative to the pivot of the stair or ladder that a very slight force is required to initiate an upward movement of the stair from an inclined position toward the horizontal. Such arrangement is made in order that the counterbalancing-weight may neutralize the effect of accumulations of ice and snow which may adhere to the ladder or stair on one side of the pivot in excess of the amount adhering to the extension-arm and truss-rod on the opposite side of the pivot. A stop-rod 26 is mounted in and projects horizontally from the wall of the building and serves as a rest to limit the downward movement of the extension-arm 16 and maintain the horizontal positioning of the stair or ladder and extension-arm against the gravity of the disk 22. The disk 22 and hanger 21 may be adjusted along the truss-rod 17 for the purpose of determining the amount of force necessary to oscillate the ladder or stair and to regulate the stability with which said weight will maintain either posi-

tioning of the stair or ladder at the extremities of its movement.

35

I claim as my invention—

1. The counterbalancing-stair for fire-escapes, comprising the stair pivoted to a suitable support, an extension-arm on said stair, a truss-rod connecting said extension-arm and stair and a counterbalancing-weight suspended on said truss-rod and arranged to swing across the axis of pivoting of the stair.

40

2. The combination of the stair, the twisted spring-rod 18 longitudinally of and below the central portion of said stair and fixed at its ends thereto, the extension-arm on said stair, the truss-rod connecting the extremities of the stair and extension-rod, the pivot-rod on which said stair is pivotally mounted and the counterbalancing-weight suspended on said truss-rod and arranged to swing across the axis of the pivot-rod in an angular adjustment of said stair.

45

3. The combination of the stair pivotally mounted and arranged for angular adjustment, a truss-rod on said stair and a counterbalancing-weight suspended from said truss-rod and arranged to swing across the axis of pivoting of the stair.

55

Signed by me at Des Moines, Iowa, this 23d day of January, 1902.

PETER L. LARSON.
